UNITED STATES PATENT OFFICE.

JOHN S. WORTH AND WILLIAM F. HARRISON, OF COATESVILLE, PENNSYLVANIA,
ASSIGNORS TO JOHN S. WORTH AND WILLIAM P. WORTH, OF COATESVILLE, PENN-
SYLVANIA.

TUBE AND BAR TROUGH.

1,007,510.

Specification of Letters Patent. Patented Oct. 31, 1911.

Application filed July 30, 1909. Serial No. 510,440.

To all whom it may concern:

Be it known that we, JOHN S. WORTH and WILLIAM F. HARRISON, citizens of the United States, residing in Coatesville, Pennsylvania, have invented certain Improvements in 5 Tube and Bar Troughs, of which the following is a specification.

The object of our invention is to construct 10 automatic means for discharging tubes, rods, etc., from the troughs or guides which receive the tube or rod from the mill or straightening machine.

A further object of the invention is to so 15 construct the apparatus that the mechanism can be actuated by hand as well as by power means, and a further object of the invention is to so construct the mechanism that a tube of any length can automatically trip the delivery mechanism.

20 In the accompanying drawings, Figure 1, is a front side view of one end of a tube trough illustrating our invention, Fig. 2, is an end view, Fig. 3, is a rear view; Fig. 4, is a sectional plan view on the line 4—4 25 Fig. 1, Figs. 5, 6 and 7 are diagram views showing the mechanism in different positions, Figs. 8, 9, 10, 11, 12 and 13 are views illustrating details of the invention, and Fig. 30 14, is a vertical sectional view on the line 14—14, Fig. 2.

Our invention is particularly adapted for 35 use in tube mills, and the present machine is located directly back of the straightening rolls and receives the tube from the straightening rolls and discharges the tube from one side on to a series of guides which direct the tubes to a test station or storage pile, but it will be understood that the invention can be used in handling rods as well as 40 tubes without departing from the essential features of the invention, and can be located at any point in the mill and at the rear of any of the several machines making up a series in the manufacture of tubes or rods.

45 A is a trough, V-shaped in cross section and adapted to receive the tube in the present instance from the straightening rolls. In the drawings we have only shown the end of the trough farthest from the rolls, 50 as the invention relates particularly to that portion of the mechanism.

B is a shaft mounted in bearings b at one side of the trough A and on this shaft are a series of arms B' shaped to conform to the 55 shape of the trough, so that the end arm

swings clear of the trough, but the intermediate arms pass through slots α in the trough, as clearly shown in Fig. 1. As motion is imparted to the shaft B after the tube is in the trough and the mechanism 60 is shifted to turn the shaft B, then one set of arms B' will pick the tube out of the trough and deliver it to skids or guides at one side of the machine.

Our invention relates to certain improvements in automatic mechanism for actuating the shaft B and for bringing the stop mechanism back to its original position. On the shaft B is a pinion b' which meshes with a gear wheel c on a shaft C mounted in a 70 frame A' depending from the trough A. On the shaft C, in the present instance, is another wheel c' which meshes with a rack d on a piston D adapted to the cylinder E having a bracket E' secured to the frame A'. 75 This is a hydraulic cylinder and the fluid under pressure is admitted through the pipe e from the hydraulic valve E' which is connected to the source of fluid supply. Carried by the piston D is a cross-head D' from 80 which are suspended rods d' carrying weights D² in the present instance, one on each side of the cylinder E. The weights are sufficient to return the piston to starting point after the pressure has lifted the piston 85 to full upward stroke required.

F is a trip lever which is located at the end of the trough A and in line so as to be struck by the tube as it is fed through the trough. The tube is fed with such force 90 that it will move the arm back to the position shown by dotted lines in Fig. 1, and this movement will throw in the mechanism for turning the shaft B so that its arms will lift the tube out of the trough. The trip 95 lever F is mounted on a shaft F' adapted to a bearing g on a bracket G secured to the frame A' and on the end of the shaft opposite to the lever F is a gear wheel f which meshes with the gear wheel i on a shaft I 100 mounted in bearings g' forming part of the bracket G. The other arm f' of the lever F is connected by a rod f² to the rod h⁴ of the valve H', and the piston rod h of the steam cylinder H is connected to the valve stem e' 105 of the valve E' by links h' and a lever h², one arm of this lever being connected to a link h³ pivoted to the valve casing E'. The lever is also provided with a handle by which it can be operated by hand in the 110

event of the hydraulic mechanism being out of order.

While we have described the cylinder H as a steam cylinder, it can be operated by 5 compressed air or gas, and the type of the valve E' will depend upon the fluid used in the cylinder E.

Mounted on the shaft I is a lever M having an adjustable weight m^2 on one arm m , 10 the other arm m' is forked and spans a shifting rod N secured at its lower end to one of the weights D². One portion of the hub of this lever is in the form of a segment, Fig. 9 and the hub of the pinion i is 15 also in the form of a segment, Fig. 11, so that when they are set in position there is a certain amount of lost motion before the two segments contact. Mounted on a stud m^3 on the arm m' is a trip pawl p having 20 one arm p' arranged so as to be struck by the projection n' on the adjustable trip collar n . The trip pawl has a nose p^2 which engages a plate g^2 on the bracket G and holds the lever M until the trip pawl is 25 tripped by the rod N as it is raised on the upward movement of the piston D and the lost motion between the lever M and the gear wheel i is sufficient to allow the gear wheel to move as the lever F is moved outward as 30 it is struck by the tube. By this means the apparatus is made automatic so that after the lever is tripped the weight will carry the lever M down as in Fig. 6, returning the lever F to its normal position and reversing the 35 valve in the valve chest E' so as to allow the fluid to escape from the cylinder E, causing the piston D to reverse its movement as well as the rod N. Thus the mechanism is entirely automatic and is under the control of 40 the tube.

In some instances short tubes may be made which would not travel the full length of the trough A. In this event we mount a rod S in roller bearings s at the side of the 45 tube trough and on this rod is an arm S' which enters the trough so as to be struck by the tube and on the end of the shaft S is an arm S² which is slotted to allow it to pass over the end of the lever F, so that any motion imparted to the rod S will actuate the 50 lever F. The arm S' is adjustable on the rod S, being fastened to the rod by set screws s', and has a roller s², in the present instance, which rests on the inner edge of the trough 55 so as to allow it to travel freely. When long tubes are being made the arm S' can be thrown back out of the trough as well as the arm S².

The operation of the mechanism is as follows: If the tubes are long, then the rod S is 60 shifted so that the tube will strike the lever F and the moment the tube strikes the lever it will force it out, as shown by dotted lines in Fig. 1, and the parts will assume the 65 position as shown in the diagram Fig. 5.

The lever M will be held by the trip pawl p and the piston D will rise, carrying with it the weights and operating the shaft B, causing the arms B' to travel and engage the tube within the trough A and lift it out of 70 the trough until it rolls to one side clear of the mechanism. When the arm is in position to allow the tube to roll to one side the trip collar n will trip the pawl p , releasing it as in Fig. 5, and immediately the lever M 75 will turn to the position shown in Fig. 6, returning the lever F to its normal position, as shown in full lines in Fig. 1. As the lever F returns to its position, the valve H' is 80 shifted operating the piston in the cylinder H which in turn shifts the valve in the chest E' and the fluid is allowed to escape from the cylinder E. The weights D² cause the piston D to move down and the rod N will also move down. The collar n^2 will then 85 strike the arm m' of the lever M, as shown in Fig. 7, and will move it, lifting its weight m^2 until the trip pawl p engages the plate g^2 , as indicated in Fig. 1, when it will hold the lever M until the trip pawl is again released by the collar n .

We claim:—

1. The combination of a trough, a rotating shaft having arm for removing a tube or bar from the trough, a trip lever pivoted to a bearing and projecting at the end of the trough so as to be actuated by a tube traveling in the trough, with means for imparting motion to the rotating shaft, and devices between the said means and the trip lever for 95 throwing said means into action, and means for returning the trip lever to its normal position after the tube has been removed from the trough.

2. The combination of a trough, a rotating shaft located at one side of the trough, arms on said shaft for removing the tube or bar from the trough, mechanism for rotating said shaft, a trip lever pivoted to a bearing and located at the end of the trough 100 so as to be actuated by a tube traveling through the trough, mechanism for operating the shaft to remove a tube from the trough, a weighted lever, gearing between the said weighted lever and the trip lever, 105 said gearing being so constructed that there is a certain amount of lost motion, means controlled by the mechanism for operating the shaft, said means controlling the position of the weighted lever whereby sufficient 110 time is given for the removal of a tube before the trip lever is returned to its normal position.

3. The combination of a trough, a shaft located at one side of the trough, arms on 125 the shaft for removing a tube or bar from the trough, a cylinder, a piston mounted in the cylinder, a rack on the piston, a gear wheel meshing with the rack and geared to the said shaft, a trip lever pivoted at the 130

end of the trough, a weighted lever geared to the trip lever, a rod carried by the piston and having means for actuating the weighted lever, a valve connected to the trip lever so that on the movement of the trip lever by a tube or bar in the trough, the valve will be shifted to cause the piston to move and turn the shaft and to set the trip lever through the medium of the weighted lever after the tube or bar has been removed from the trough.

4. The combination of a trough, a shaft, means connected to the shaft arranged to shift a tube or bar out of the trough when said shaft is rotated, a cylinder, a weighted piston, gearing between the piston and shaft through which the shaft is turned, a valve for controlling the admission of fluid to the cylinder, a rod having connection with the weighted piston and having actuating collars, a pivoted trip lever arranged in operative position relative to the trough, a gear wheel movable by the lever at one time and for moving said lever at another time, a second gear meshing with the first gear, a second lever adapted to be moved by one of the collars to normal position, a trip pawl on said second lever adapted to engage an element and hold said lever in its normal position, means between the second gear and the second lever so arranged that there is a given amount of lost motion to allow the gear to operate a limited amount without a movement of the lever so that the trip lever can be moved back and will not be returned to its normal position until the bar or tube is clear of the trough, means for connecting the trip lever and valve for opening the latter when the former is moved out of normal position, the arrangement of elements being such that one of the collars will engage and release the trip pawl when the piston has been moved the proper distance, and means connected to the second lever to return the first lever to its normal position after the disengagement of the trip pawl, the said movement of the first lever by the second lever being effected through the meshing gears, the means operating with said gears and levers.

5. The combination of a trough, means for removing a tube or bar from the trough, a trip element for automatically actuating said means, a rod mounted at one side of the

trough, an arm on the rod arranged to engage the trip lever, an adjustable arm on the rod adapted to rest on the trough in the path of the tube, said arm being free to rotate so that it can be moved into or out of the trough so that a tube or bar traveling in the trough will either strike said arm or the trip lever to actuate the mechanism for removing said tube or rod from the trough.

6. The combination of a trough, means for removing a tube from the trough, a weighted piston geared to the said means, a rod attached to the weighted piston, a pivoted trip lever mounted at the end of the trough to be actuated by a tube or rod passing through the trough, a weighted lever geared to the trip lever and having an arm actuated by projections on the rod, a latch on the weighted lever also actuated by one of the projections on the rod, a valve, a valve rod connected to the trip lever, a cylinder, a piston in the cylinder controlled by the valve, and a main valve controlled by said piston, the valve in turn controlling the movement of the weighted piston.

7. The combination of a trough, a shaft, arms on the shaft for removing a tube or rod from the trough, a cylinder, a weighted piston therein geared to the said shaft, a rod on the weighted piston, projections on the rod, a trip lever located so as to be actuated by a tube or rod passing through the trough, a weighted lever, gearing between the weighted lever and the trip lever, the gearing being so arranged that there is a certain amount of lost motion, a valve, a piston in the valve connected to the trip lever, a cylinder, a piston in the cylinder controlled by the valve, a main valve, lever mechanism connecting the main valve with the said piston, and a handle on said mechanism so that the valve can be actuated by hand, said main valve controlling the admission of fluid to the cylinder in which the weighted piston is mounted.

In testimony whereof, we have signed our names to this specification, in the presence of two subscribing witnesses.
